UNITED STATES PATENT OFFICE.

FRANK R. PIPKIN, OF GREENFIELD, ARKANSAS.

RAILROAD-SPIKE.

1,338,154.

Specification of Letters Patent. Patented Apr. 27, 1920.

Application filed October 6, 1919. Serial No. 328,839.

To all whom it may concern:

Be it known that I, FRANK R. PIPKIN, a citizen of the United States, residing at Greenfield, in the county of Poinsett and State of Arkansas, have invented certain new and useful Improvements in Railroad-Spikes, of which the following is a specification.

This invention relates to spikes specially adapted for use in securing railroad rails to the cross-ties of the road bed, and to prevent the rails from spreading laterally; and it consists in the novel construction of the spike and its head as hereinafter fully described and claimed.

In the drawings, Figure 1 is a side view of a railroad spike constructed according to this invention. Fig. 2 is an end view, and Fig. 3 is a plan view, of the same.

The shank 2 is preferably straight and rectangular in cross-section. Instead of the usual head, a large plate 3 is formed on or secured to the top end of the spike. This plate is preferably triangular in form, and the shank 2 projects from its apex end portion and at a right angle to its under surface, which is flat. The plate is thickest at its apex end portion, and it tapers gradually from its apex portion to the other side or end opposite to its apex portion.

A notch 5 is formed in the underside of

the apex portion of the plate on the other side of the spike from the main portion of the plate. This notch fits over the flange of the rail, a portion of which is indicated 35 in dotted lines in Fig. 1. The narrow end of the plate 3 is preferably about three times as wide as the shank, its broad end is substantially twice the width of its narrow end, and the plate is longer than its greatest 40 breadth.

The spike is driven into the wooden cross-tie alongside the rail, and the flat underside of the plate bears on the top of the cross-tie, and prevents the spike and rail 45 from being pressed laterally by the side pressure of the wheel flanges of the wheels of the locomotive engines and cars.

What I claim is:

In a railroad spike, a shank having a 50 relatively long and substantially triangular plate the narrow end portion of which is secured to the top of the shank and which is substantially three times as wide as the shank, the broad end of the plate being substantially twice as wide as its narrow end, 55 and said plate having a flat underside of relatively large area which bears on the tie when the shank is driven into it.

In testimony whereof I have affixed my 60 signature.

FRANK R. PIPKIN.
